UNITED STATES PATENT OFFICE.

CHARLES ERNEST JONES, OF CHICAGO, ILLINOIS.

DESIGN FOR A HANGER FOR LIGHT-REFLECTING BOWLS.

44,844.

Specification for Design.

Patented Nov. 4, 1913.

Application filed July 28, 1913. Serial No. 781,661. Term of patent 3½ years.

To all whom it may concern:

Be it known that I, CHARLES ERNEST JONES, a citizen of the United States, resident of the city of Chicago, county of Cook, and State of Illinois, have invented a new, original, and ornamental Design for Hangers for Light-Reflecting Bowls, of which the following is a specification, reference being had to the accompanying drawings, forming a part thereof.

Figure 1 is a side elevation of a hanger

for light reflecting bowls, and Fig. 2 is a front elevation thereof showing my new design.

I claim:

The ornamental design for a hanger for light reflecting bowls as shown.

CHARLES ERNEST JONES.

Witnesses:

JOHN H. McELROY,
JNO. G. ELLIOTT.
